Primary Examiner — Natasha Vujevic(74) *Attorney, Agent, or Firm* — Manabu Kanesaka(57) **CLAIM**

The ornamental design for air conditioner panel, as shown and described.

DESCRIPTION

FIG. 1 is a perspective view of an air conditioner panel showing my new design;

FIG. 2 is a front view thereof;

FIG. 3 is a plan view thereof;

FIG. 4 is a bottom view thereof;

FIG. 5 is a left side view thereof; and,

FIG. 6 is a right side view thereof.

The broken lines depict portions of the air conditioner panel that form no part of claimed design.
